MEANS FOR SAVING FUEL IN INTERNAL-
COMBUSTION ENGINES

Abraham Weiss, New York, N. Y.

Application April 17, 1945, Serial No. 588,818

10 Claims. (Cl. 123—52)

1.

This application relates to means for saving fuel in internal combustion engines for motor vehicles, or the like.

The principal object of this invention is the provision of means for controlling both the exhaust and intake valves of the cylinders by automatically operated sets of cams, so that according to the speed of the engine or vehicle, the valve action of said cylinders will be changed to render some or all of the cylinders ineffective, to save fuel.

With this and other objects in view, my invention consists in the novel construction, combination and arrangement of parts, as will be hereinafter more fully described and defined in the appended claims.

In the accompanying drawing, which constitutes part of this specification and in which similar reference characters denote corresponding parts:

Fig. 1 is a diagrammatic view of one embodiment of my invention employing mechanical means for controlling the action of the cylinder valves;

Fig. 2 is a similar view of another embodiment employing electric means for the same purpose;

Fig. 3 is a diagrammatic view of a third modification of the electric means;

Fig. 4 is a top plan view of a still other modification, applicable to engines with overhead valves operated through rocker arms; and

Fig. 5 is a cross-section on line 5—5 of Fig. 4.

Referring first to the modification shown in Fig. 1, 10 denotes a multiple cylinder engine, 11 and 12 denote the exhaust and intake valves of the different cylinders (in the present example, only two cylinders are shown).

13 denotes an engine driven rotary shaft which is capable of longitudinal displacement in its bearings 13a and on which are fixed pairs of cams 14 for the exhaust and intake valves 11 and 12, one pair for each cylinder. Each cam 14 is a composite of four inter-connected or integral sections arranged contiguously to one another. The sections of the cams are so shaped that according to their position relative to the corresponding cylinder valves, the latter will be caused to either operate normally, or open or close as will be hereinafter explained to render the cylinders ineffective.

Thus in a multiple cylinder engine the cams 14 for the exhaust valves 11 of any predetermined set of cylinders, as for instance in a four cylinder engine, the first and third cylinder have each a single cam section 14a adapted to operate said

2.

valve normally; i. e., open and close during the cyclic operation of the engine. The cams 14 for the intake valves 12 of said pair have each a single cam section 14b adapted to open and close said intake valves normally. Contiguously disposed to one another and to each of said sections 14a on the cams 14 for the exhaust valves 11 of said pair of cylinders are two uniform end sections 14c, 14d adapted upon two successive displacements of the cam shaft 13 in the same direction to open and keep open the said valve. The cams 14 for the intake valves 12 of said pair of cylinders have two uniform similarly disposed contiguous sections 14e, 14f adapted by the same displacements of said shaft to close and keep closed said intake valve. The cams 14 for the exhaust and intake valves of another pair of cylinders, say second and fourth, in a four cylinder engine may each be constructed as follows:

20 A section 14g of each of said cams is adapted normally to open and close the exhaust valve 11 of said cylinder, a second section 14h of same shape similarly disposed and contiguous to said section 14g is adapted to continue to operate normally said exhaust valve on the first of the two above named displacements of the shaft 13 in the same direction, and an end section 14i contiguous to said section 14h adapted at the second displacement of said cam shaft to open and keep open the said exhaust valve. The cams for the intake valves 12 of the same pair of cylinders may each have a section 14j adapted to operate normally said valve, a similar contiguous section 14k to continue the normal operation at the first displacement of the cam shaft in the same direction, an end section 14l continuous to the last named section adapted at the second displacement of the shaft to close said valve.

Each cam at its opposite end has a cam section 40 14m adapted on the displacement of the shaft in opposite direction to cause all valves to close, so that the pistons working in said cylinders will produce a braking effect. This may be desired when the vehicle travels down a steep grade.

45 The means for causing the displacement of the cam shaft 13 according to the speed of the engine are automatically controlled through the accelerator and brake pedals A, B, respectively, as well as a speed actuated means G, such as a governor, in the manner to be presently described.

In the example shown, the cam shaft 13 is operatively connected by suitable means, such as a system of levers 15, or the like, to a second longitudinally movable shaft 16 extending through a housing 17, partitioned as at 17¹ into two com-

partments 17a and 17b. Fixed on the shaft 16 and movably bearing in the compartment 17a of said housing is a plunger 18 provided with a sleeve-like extension 18a which can pass through a central hole 17² provided in the partition 17¹ of said housing.

Mounted on the shaft 16 and movably bearing in the compartment 17b of the housing 17 is a second plunger 19. This plunger is connected to the shaft by slot and pin 19a and 19b, or the like, so as to be capable of a limited independent displacement thereon. The plungers 18 and 19 are adapted to be acted upon by pressure fluid from an engine driven pump 20 in the following manner:

21 is a fluid pressure distributing chamber which through conduit 22 communicates with the pump 20 and by conduits 23 and 23a is connected to the compartments 17a and 17b. The flow of the pressure fluid through the conduits 23, 23a into the compartments 17a, 17b is controlled automatically through a cock mechanism 24¹, 24² capable of being actuated by the accelerator and brake pedals A, B, respectively. The flow of the fluid into the compartment 17a through the conduits 23 is additionally controlled by the speed actuated mechanism G. The conduit 23b serves as a fluid return conduit and under the control of governor G leads from the compartment 17a back into the pump 20 or its reserve tank 20a.

When the cock 24¹ is open, as shown, the fluid pressure entering the compartment 17b at the rear of plunger 19 will move said plunger 19 to the left, and after its independent motion on the shaft 16 due to its play thereon, move the latter in the same direction, whereby cam shaft 13 will receive a partial displacement to the right and thereby place the sections 14c, 14e, 14h and 14k adjacent to the normally operating cam sections 14, 14b, 14g and 14j, respectively, in range with the corresponding cylinder valves. The fluid pressure entering the compartment 17a when the governor actuated valve 25 is open will displace the plunger 18 more to the left, as a result of which the shaft 16, and consequently the cam shaft 13 will receive a second displacement in the same direction as before, and bring the next adjacent cam 14d, 14f, 14i and 14l into the range of the corresponding valves.

The cock 24¹ controls the passage of the fluid pressure from pump 20 into the conduit 23 and the cock 24² controls the passage of the pressure fluid from compartment 17a back into the pump 20 or its reserve tank 20a. The cock mechanism is actuated through a push rod 26 projecting into the path of the accelerator A and an auxiliary push rod 26¹ projecting into the path of the brake pedal B and slidably connected to push rod 26.

To be actuated by the brake pedal B is a fluid distributing valve 27, or the like, which when said pedal is depressed through a lever 28, or the like, will open communication between pump 20, distributing chamber 21 and compartment 17b in front of plunger 19. This will cause the plungers 18 and 19 to move to the right, whereby the cam shaft 13 will be moved to the left.

Thus when accelerator A and brake B are off, as shown, and the vehicle is running with slow speed, or idling, the particular sections of the cams 14 on the partially displaced cam shaft 13 will cause the exhaust valves 11 of some of the cylinders to open, while the intake valves 12 of said cylinders will be caused to close, admitting no fuel, and thus rendering said cylinders entirely ineffective.

The same will be true if the vehicle assumes a certain speed, with the accelerator pedal off; i. e., some of the cylinders will be rendered ineffective, for the governor actuated valve 25 being then open will permit pressure fluid to enter also compartment 17a, and effect a second displacement in the same direction of shaft 16 to the extent of the play between the latter and plunger 19. By this second displacement, the exhaust valves of the same set of cylinders will continue to remain open and the intake valve closed, as in the first position, so that said set of cylinders will be again ineffective and not consume fuel.

On the depression of brake B, pressure fluid from pump 20 in front of plunger 19 will displace shaft 16 in the opposite direction, with the result that cam shaft 13, too, will be shifted in the opposite direction, causing the operation of all cylinder valves at timed periods.

In the modification shown in Fig. 2, the operation of the cylinder valves 11, 12 through multiple cam sections 14 mounted on a driven and longitudinally displaceable shaft 13 is the same as in the first modification. Here, however, the operation of the cam shaft is controlled electrically. To this end, the displacement of the shaft 16, and consequently of cam shaft 13, is effected through three separate solenoids 32, 33 and 34 mounted around metal shaft 16. These solenoids are energized by electric circuits controlled from the accelerator pedal A and brake pedal B. Included in these circuits are manually operable make and break mechanism 35 and a speed actuated make and break mechanism 36. The first named make and break mechanism comprises two pairs of contact fingers 35a, 35b rotatably mounted on a pin or axle 37 and manipulable by an arm 38 projecting into the path of the accelerator pedal A from a sliding bar 39 having a catch 40. This catch when the pedal A is fully depressed will engage arm 37¹ and displace the contact fingers 35a, 35b.

The make and break mechanism 36 of well-known construction has a number of contacts 41, 41a, 41b, 41c that through the action of a generator (not shown) or other speed control will make or break said contacts. At low speed when the solenoid 42 is disengaged, the contacts 41a, 41b, 41c will be open, while contact 41 will be closed, and vice versa. With the accelerator A in off position, the current will flow from the source of power E along wires a and closed contact 41 to solenoid 32. At high speed the current will flow along wire a, contact 41a to solenoid 32 and also through wires b and contact 41b to solenoid 33. When the brake pedal B is depressed at high speed, the solenoid 34 will be energized by the current flowing from the source along lines c and closed contact 41c.

The solenoid 32 is mounted around a metal core 16a which by slot and pin 16¹, 16² is connected to the shaft 16 so that when said solenoid is energized it will cause a limited displacement of the shaft 16 equal to the width of a cam section, as in the first described modification.

When the solenoid 33 is energized, it will cause a further displacement of the shaft 16 and consequently of the cam shaft 13, with the same results as heretofore described.

When the accelerator A is fully depressed, it will cause the contact fingers 35a, 35b to break the contacts for the solenoids 32, 33 permitting the shaft 16 by its spring force to return to normal. By depressing the brake pedal B at speed, the current will flow through wires c, contact

41c, energizing solenoid 34 in reverse direction and thereby causing the cam shaft 13 to move so as to operate all valves, with the results as already described.

In the modification shown in Fig. 3, two separate pedals A, A¹ and a brake pedal B are employed. In this case, the manual make and break mechanism 35 is eliminated. The arrangement of the solenoids 32, 33 and 34, shaft 16 and cam shaft 13, valves 11 and 12 are the same as in the aforescribed modification of Fig. 2, and for simplicity's sake are omitted. When both accelerators are in off position and the speed of the engine or vehicle is low, the current will flow from the source along the wires a and closed contact 41 to the solenoid 32 and at high speed along both wires a, b to both solenoids 32, 33, and when the brake pedal is depressed it will flow along the wire c to solenoid 34 with the effect already described.

By depressing only accelerator A, with the brake B being off, the circuit through all solenoids will be broken and the shafts 16 and 13 moved by spring force into normal position, so that all cylinder valves will be caused to operate normally.

By depressing only accelerator A¹ at low speed, the circuit will flow only through solenoid 32, so that only part of the cylinder will be rendered ineffective.

In the modification shown in Figs. 4 and 5, 43 denotes a multiple cylinder engine having overhead valves 44, 45 which are operated by rocker arms 46 impelled from a driven cam shaft 47 in well-known manner. To control the valves according to the speed of the engine, each rocker arm 46 is not fixed to the rocker shaft 48, but straddles thereon through a depending yoke 49. Fixed to the rocker shaft is a cam 50 which is capable of lifting the rocker arm sufficiently out of the path of the cylinder valve so as not to affect the latter during the operation of the engine. The rocker shaft 48 is operatively connected as at 51 to the armature 52 of the solenoid 53, which may be energized by a generator (not shown). The cams 50 on the rock shaft 48 may be of appropriate shape calculated according to speed to lift the corresponding rocker arm so as to close or open the corresponding cylinder valves and produce the effect heretofore described.

Various other modifications may be made without departing from the spirit of my invention, and I therefore do not wish to restrict myself to the details described and shown.

What I claim is:

1. In a multiple cylinder internal combustion engine having an intake and exhaust valve in each cylinder, means for automatically causing the intake valves to close and the exhaust valves to open so as to render said cylinders temporarily ineffective at predetermined speeds of said engine, said means including driven displaceable members adapted to actuate said valves, speed responsive means and manual means, both said last means being adapted in cooperation to control the displacement of said members, and means capable of restoring the effectiveness of said cylinders irrespective of speed.

2. In a multiple cylinder internal combustion engine having an accelerator, an intake and exhaust valve in each cylinder, means for automatically causing the intake valves to close and the exhaust valves to open so as to render said cylinders temporarily ineffective at predetermined speeds of said engine, said means including driven displaceable means adapted to actuate said valves, speed responsive means and accelerator actu-

5 ated means adapted in cooperation to control the displacement of said means, and means capable of restoring the effectiveness of said cylinders irrespective of speed.

3. In an internal combustion engine, a cylinder having an intake and an exhaust valve, means for automatically causing the intake valve to close and the exhaust valve to open at a predetermined speed of the engine to render said cylinder ineffective, said means including a driven set of contiguous valve actuating cams of predetermined shapes displaceable relative to said valves and speed responsive means and manual means adapted in cooperation to cause the displacement of said cams.

4. In a multiple cylinder internal combustion engine, each cylinder having an intake and an exhaust valve, means for automatically causing some of the cylinders to become ineffective at a certain low speed, and all cylinders to become ineffective at a certain high speed, said means including a set of contiguous valve actuating cams of predetermined shapes for each valve, said cams being displaceable in unison relative to said valves, so that according to the extent of displacement of said cams and their shapes, the intake valves of some or all of the cylinders will be caused to close and the exhaust valve thereof to open, and speed responsive means and manual means adapted in cooperation to cause the displacement of said cams.

5. In an internal combustion engine having an exhaust and intake valves, means for causing said valves of some of said cylinders at predetermined speeds of the engine to render said cylinders temporarily ineffective, said means including a driven displaceable shaft, a plurality of cams thereon for actuating each valve, means for causing the displacement of said cam shaft and cams transversely to said valves, said means including fluid pressure means, speed actuated means and manual means, both said last named means serving to control the said fluid pressure means.

6. In a multiple cylinder internal combustion engine having exhaust and intake valves, means for causing said valves at predetermined speeds of said engine to render some of said cylinders temporarily ineffective, said means, including a driven displaceable shaft, a plurality of cams thereon for actuating each valve, means for causing the displacement of said cam shaft and cams transversely to said valves, said means including a housing, displaceable members therein operatively connected to said cam shaft, means for operating said displaceable members, speed actuated means and manual means, both said last named means serving to control the operation of said displaceable members.

7. In an internal combustion engine according to claim 6, in which said displaceable means include a shaft and a pair of plungers mounted thereon, one of said plungers being capable of limited movement on said shaft independent of the second plunger, for the purpose specified.

8. In a multiple cylinder internal combustion engine having exhaust and intake valves, means for causing the intake valves to close and the exhaust valves to open at predetermined speeds of said engine, said means, including a plurality of driven displaceable members for actuating each valve, means for causing the displacement of said members relative to said valves, including electric means for actuating said last named means, speed actuated means and manual means,

both said last named means serving in cooperation to control said electric means.

9. In a multiple cylinder internal combustion engine, according to claim 5, in which said fluid pressure means include a fluid pressure pump and a fluid pressure distributor.

10. In a multiple cylinder internal combustion engine according to claim 8, in which said electric means include a plurality of solenoids, speed actuated make and break mechanism and manually actuated make and break means, said speed actuated make and break mechanism and said manual means in cooperation with one another serving to control the circuits through said solenoids.
